Filed Nov. 15, 1966, Ser. No. 4,671

Term of patent 14 years

(Cl. D61—1)

FIG. 1

FIG. 2

FIG. 3

FIG. 4

FIG. 5

FIG. 6

FIG. 1 is a front elevational view of a photographic camera or similar article, showing our new design;

FIG. 2 is a side elevational view;

FIG. 3 is a rear elevational view;

FIG. 4 is an opposite side elevational view;

FIG. 5 is a top plan view; and

FIG. 6 is a bottom plan view thereof.

Portions of the drawing figures are stippled to indicate contrast in appearance, and portions are diagonally lined to indicate transparency. Portions which are both diagonally lined and stippled indicate a transparent surface behind which a darkened opaque surface is visible.

We claim:

The ornamental design for a photographic camera or similar article, substantially as shown and described.
